(57) **CLAIM**

The ornamental design for a mounted display screen, as shown and described.

DESCRIPTION

FIG. 1 is a rear view of a mounted display screen according to the present invention.

FIG. 2 is an enlarged rear view of the mounted display screen.

FIG. 3 is a front view of the mounted display screen.

FIG. 4 is an enlarged front view of the mounted display screen.

FIG. 5 is a right side view of the mounted display screen.

FIG. 6 is an enlarged right side view of the mounted display screen.

FIG. 7 is a left side view of the mounted display screen.

FIG. 8 is a top view of the mounted display screen.

FIG. 9 is an enlarged top view of the mounted display screen.

FIG. 10 is a bottom view of the mounted display screen.

FIG. 11 is a rear view of the mounted display screen of FIG. 1 in an alternate position of use, with the display screen in a vertical configuration.

FIG. 12 is an enlarged rear view of the mounted display screen in the alternate position of use of FIG. 11.

FIG. 13 is a front view of the mounted display screen in the alternate position of use of FIG. 11.

FIG. 14 is an enlarged front view of the mounted display screen in the alternate position of use of FIG. 11.

FIG. 15 is a right side view of the mounted display screen in the alternate position of use of FIG. 11.

FIG. 16 is an enlarged right side view of the mounted display screen in the alternate position of use of FIG. 11.

FIG. 17 is a left side view of the mounted display screen in the alternate position of use of FIG. 11.

FIG. 18 is a top view of the mounted display screen in the alternate position of use of FIG. 11.

FIG. 19 is an enlarged top view of the mounted display screen in the alternate position of use of FIG. 11; and,

(Continued)

FIG. 20 is a bottom view of the mounted display screen in the alternate position of use of FIG. 11. The dash-dash broken lines in FIGS. 1-20 illustrate environmental subject matter and portions of the mounted display screen that form no part of the claimed design. The dash-dot-dash broken lines in FIGS. 2, 4, 6, 9, 12, 14, 16, and 19 illustrating the boundaries of the enlarged views form no part of the claimed design.
